UNITED STATES PATENT OFFICE.

WILLIAM I. HALDEMAN, OF PINE GROVE, PENNSYLVANIA.

CHICKEN-COOP.

1,180,032.

Specification of Letters Patent.

Patented Apr. 18, 1916.

Application filed June 24, 1915. Serial No. 36,065.

To all whom it may concern:

Be it known that I, WILLIAM I. HALDEMAN, a citizen of the United States, and a resident of Pine Grove, in the county of Schuylkill and State of Pennsylvania, have invented certain new and useful Improvements in Chicken-Coops, of which the following is a specification:

My invention relates to coops for housing chicks and chickens, and one of the main objects thereof is to provide a coop which will protect the former from being over-run by the latter at feeding time by permitting the chicks to enter the coop bodily to feed but bodily excluding the chickens although permitting the entrance of their heads and necks.

A further object is to form the coop of two members movable with respect to each other, whereby chicks or chickens may be cooped up at night in absolute safety from marauding cats, rats, and the like.

A further object is to make the movable members separable, whereby they may be used independently, as for segregating either roosters, cockerels, or hens, at will, for reasons well known to chicken-raisers.

My invention is fully described in the following specification, of which the accompanying drawings form a part, in which like characters refer to like parts in each of the views, and in which:

Figure 1 is a perspective view of one of the members of my coop, with the disinfectant element in operative position; Fig. 2 is a similar view of the other member of my coop; Fig. 3 is a view of the coop in its entirety, for protecting the chicks or chickens housed therein at night; and Fig. 4 is a sectional view of the coop as an entirety in position for feeding both chicks and chickens, and at the same time disinfecting both.

When both chicks and chickens are fed in the open the latter over-run the former in their eagerness to secure their food, with the result that the former are sometimes injured and frequently underfed. This I overcome by providing a coop which, in one adjustment of its parts, permits the chicks free entry to the coop but bars the chickens entry further than their shoulders.

My invention consists of two members 5 and 6 independent of each other if desired and of practically identical construction. Both are formed of horizontally arranged

hoops 7, 8, and 9, joined by vertical bars 10 which are horizontally bent over the hoops 7 to form a roof, being joined at their upper ends to a ring 11. The distinction between 60 the two consists in making the ring 11 of the member 5 larger than that of the member 6, and also making the hoops 7, 8, and 9, of the former of slightly greater diameters than those of the latter, although this is not 65 essential, whereby the member 5 may telescope or nest over the member 6.

In practice, I prefer to arrange the vertical bars 10 in groups forming sectors with open spaces therebetween, as is clearly shown 70 in Figs. 1, 2, and 3, the bars 10 of each sector being approximately three-quarters of an inch apart, and the sectors being approximately three inches apart; these spaces permit the free passage of chicks of tender age 75 but exclude chickens of larger growth.

The members 5 and 6 may be used independently of each other at feeding time, and accomplish the segregation of chicks and chickens as above described, or the two members 80 may be nested with the sectors in register and produce the same result; the members may also be rotatably adjusted with respect to each other to move the sectors slightly out of register to limit the sizes of 85 the spaces between sectors and thus limit feeding to chicks and chickens of small sizes; and the members may also be rotatably adjusted to stagger the sectors, as shown in Fig. 3, to prevent the entry of animals and 90 thus protect the occupants; the coop may also be used in this form of adjustment to segregate and feed either chicks, cockerels, hens, etc.

The coop may be made in various sizes 95 and shapes, and structural changes may be made over the form shown and described, within the scope of the following claims, without departing from the spirit of my invention or sacrificing its advantages.

As clearly shown in the drawings, I may employ a band 12 of absorbent material adapted to contain a disinfectant on the outer side of the coop, this band being shown as slitted at spaced intervals transversely thereof and at both edges to form 105 staggered flaps 13 and 14, this band being made the subject matter of my application for Letters Patent filed November 19, 1915, Serial No. 62,336. A grown chicken in 110 reaching into the coop for his feed will necessarily have one of the flaps bear against

his neck and breast, whereas chicks will, in reaching out of the coop, have the flaps bear against their heads, thus transferring the disinfectant to both. This band may be made of any desired material and of any desired shape which will produce the desired result.

Having fully described my invention, what I claim as new, and desire to secure 10 by Letters Patent, is:—

1. A coop, consisting of two circular nested members rotatable with respect to each other and formed, each, of horizontal hoops and vertical bars forming the sides and roof, said members in one adjustment having their bars in register and in another adjustment having their bars out of register, to vary the spaces between adjacent bars.
- 15 2. A coop, consisting of two circular

nested members having their side walls in close relationship with each other, said members being formed, each, of horizontal hoops and vertical bars, and being rotatably adjustable with respect to each other to vary 25 the distances between adjacent bars.

3. A coop, consisting of two nested members formed, each, of supporting hoops and bars forming the sides and roof, said bars being arranged in groups to form relatively 30 large spaces between said groups, and said members being rotatably adjustable on each other.

In testimony whereof I have signed my name to this specification in the presence of 35 two subscribing witnesses.

WILLIAM I. HALDEMAN.
